(57) **CLAIM**

The ornamental design for a robotic lawnmower having antenna thereon, as shown and described.

DESCRIPTION

FIG. 1 is a perspective back view of a robotic lawnmower having an antenna thereon according to our design;

FIG. 2 is a back end view thereof;

FIG. 3 is a front end view thereof;

FIG. 4 is a side view thereof;

FIG. 5 is an opposing side view thereof;

FIG. 6 is a top view thereof;

FIG. 7 is a perspective front view thereof;

FIG. 8 is a perspective back view of another embodiment of a robotic lawnmower having an antenna thereon according to our design;

FIG. 9 is a back end view thereof;

FIG. 10 is a front end view thereof;

FIG. 11 is a side view thereof;

FIG. 12 is an opposing side view thereof;

FIG. 13 is a top view thereof;

FIG. 14 is a perspective front view thereof;

FIG. 15 is a perspective back view of another embodiment of robotic lawnmower having an antenna thereon according to our design;

FIG. 16 is a back end view thereof;

FIG. 17 is a front end view thereof;

FIG. 18 is a side view thereof;

FIG. 19 is an opposing side view thereof;

FIG. 20 is a top view thereof; and,
